UNITED STATES PATENT OFFICE.

JAMES LEATHEM, OF LEBANON, PENNSYLVANIA, ASSIGNOR TO HERMANN, AUKAM & CO., OF NEW YORK, N. Y., A CORPORATION OF NEW YORK.

SEWING-MACHINE.

1,099,655.

Specification of Letters Patent. Patented June 9, 1914.

Application filed July 5, 1912. Serial No. 707,842.

To all whom it may concern:

Be it known that I, JAMES LEATHEM, a citizen of the United States of America, and a resident of Lebanon, in the county of Lebanon and State of Pennsylvania, have invented certain new and useful Improvements in Sewing-Machines, of which the following is a specification.

My invention relates to improvements in sewing machines, and particularly in hooks and bobbin cases therefor.

My invention comprises a novel construction of hook and bobbin case so arranged relatively that the bobbin case is held within the hook by spring action and without screws or other non-resilient means; an improved bobbin case provided with a flange adapted to engage a corresponding flange or rib of a hook, both sides of said bobbin case being slit so as to form a number of springs, the flanged heads of which are adapted to engage a rib on the inner side of the hook, thereby holding the bobbin case in place within the hook; and other features herein described and particularly pointed out in the appended claims.

The objects of my invention are to facilitate the removal of the bobbin case from, and the replacement of said bobbin case in, the hook; to increase the thread-carrying capacity of the bobbin without material increase in size of the hook and bobbin case; and generally to improve and simplify the parts of sewing machines above referred to.

I will now proceed to describe my invention with relation to the accompanying drawings, and will then point out the novel features in claims.

In the drawings: Figure 1 shows a side elevation of the so called hook or member which carries the bottom and bobbin case, and which is provided with a beak or loop-receiving member. Fig. 2 shows an end view of such hook, with the bobbin case and bobbin therein. Fig. 3 shows an axial section of the hook, bobbin case and bobbin. Fig. 4 shows an end view of the hook, or loop-taker, the bobbin case and bobbin having been removed. Fig. 5 shows a side view of the bobbin case, showing particularly the tension spring; and Fig. 6 shows an end view of the bobbin case. Fig. 7 is a detail side view of the bobbin case illustrating the action of the tension-adjusting

screw. Fig. 8 shows a transverse section of Fig. 3. Fig. 9 is a fragmentary axial section of the bobbin case, illustrating the action of the tension-adjusting screw. Fig. 10 shows a fragmentary detail section of the bobbin indicating the provision in the top plate of the bobbin of grooves into which a sharp instrument may be inserted to get hold of the bobbin when it is desired to withdraw same.

In the drawings, 1 designates the hook or loop-taker which device is in general of ordinary construction, except as to the features hereinafter referred to. 2 designates the shaft of such loop-taker or hook, and 3 the side of the loop-taker beveled at 4 as is usual. This loop-taker is provided with the customary loop-receiving member or beak 5, and with the thread slot 6. The loop-taker is not provided, as has been common in the past, with a swinging gate or movable flange-section which normally holds the bobbin case in place, but is adapted to be swung to one side to permit removal of such bobbin case; but to the contrary, the side or flange 3 of the loop-taker is made continuous except for the thread slot 6, other means being provided for retaining the bobbin case in place as hereinafter described.

7 designates the bobbin case which is a hollow cylindrical member provided with the usual central post or arbor 8 for the bobbin, 9, and with the usual projecting lug, 10. The end of the arbor 8 is provided with a head 11 very slightly larger than the body of the arbor, and cut across as shown particularly in Figs. 2 and 3, so as to divide the end portion of the arbor into four springs pressing lightly against the hub of the bobbin so as to exert slight retardation to escape of the bobbin from the bobbin case, without materially interfering with the rotation of the bobbin with respect to the bobbin case. To facilitate such spring action the diameter of the arbor is decreased slightly at 12, beneath this head 11. The bobbin case is provided with a projecting rib or flange 13 adapted to rest upon the inwardly projecting rib or flange 14 of the hook 1, such flange 14 serving as a raceway or bearing for the flange 13 of the bobbin case. Slots 15 are provided in the sides of the bobbin case, as shown particularly in Fig. 5, which slots divide the side of the

bobbin case into a large number of springs. The extreme edge of the hook 1 is turned in slightly forming an inwardly turned rib 16, overlapping very slightly the flange 13 of the bobbin case, and so holding that bobbin case in place. The overlap is so slight, and the spring action of the spring sides of the bobbin case is such, however, that it is easy to force the bobbin case into or out of the hook, the spring sides of the bobbin case yielding slightly to permit this.

Upon the side of the bobbin case 7 is secured a tension spring 17, which is of usual construction, except that it is provided with a lip 18 projecting in a direction substantially parallel with the rotative action of the structure, and is adapted to be engaged by a screw 19 mounted in a suitable screw hole in the edge flange of the bobbin case. By turning this screw 19 in or out, the tension exerted by the spring 17 upon the thread may be varied as desired.

The hook 1 is provided in its side with suitable openings 21 through which a suitable instrument may be introduced to pry the bobbin case out of said hook. In inserting the bobbin case into the hook the pressure of the fingers is sufficient to press it home.

It is very desirable that hooks or loop-takers such as shown in the drawings, shall be in rotative balance. The thread slot 6 lightens the hook considerably on one side, and unless a corresponding amount of metal be taken out substantially diametrically opposite the hook is out of balance. I have found that the best way to counterbalance the hook to compensate for the absence of metal incident to the thread slot 6, is to reduce the thickness of the metal of the side of the loop-taker diametrically opposite the thread slot. To this end, and as is shown particularly in Fig. 8 the sides of the loop taker are chambered out or cut away between points 22 and 23, on the side of the loop taker opposite thread slot 6.

To remove the bobbin case from the hook, a suitable instrument is introduced through one of the openings 21, between the bottom 50 of the bobbin case and the bottom wall of the hook, and one side of the bobbin case is pried out, the spring leaves forming the greater portion of the side of the bobbin case yielding to permit this. It is then easy 55 to remove the bobbin case; and of course, once the bobbin case has been removed from the hook it is easy to remove the bobbin from the bobbin case.

In replacing the parts, the bobbin is placed within the bobbin case, and the latter is then placed within the hook and pressed home, the spring sides of the bobbin case yielding to permit the flange 13 to pass the rib 16.

To facilitate removal of the bobbin from

the structure, without removing the bobbin casing, the top plate of the bobbin is provided on its underside, with shallow radial grooves 24, extending from the hub of the bobbin out to the several holes 25. When it is desired to remove a bobbin from its bobbin case, a needle, pin, or other sharp instrument is introduced through one of these grooves 24, under the top plate of the bobbin and then by this needle or other instrument the bobbin may be pulled out. This can be done in the manner described, without any cutting or weakening of the thread wound upon the bobbin.

In the side of the bobbin case, and in proximity to the tension spring 17, and thread slot 28, the outer surface of the bobbin case is provided with a plurality of inclined thread retaining grooves 27. These grooves are quite shallow and are of such size as adapts them to hold momentarily the needle thread or top thread while it is passing around the bobbin case. As is well known, the action of a hook such as described, and of its bobbin case, in relation to the needle thread or top thread, is as follows: During the rotation of the hook or loop-taker 1, the beak 5 passes through a bight or loop of the needle thread or top thread; and continued rotation of the loop-taker carries one side of the bight of such needle thread down to the base of the thread slot 6; the other side of the bight of the needle thread being held by the needle in more or less close proximity to the lug 10 of the bobbin case. As the loop taker 1 continues to rotate the needle thread passes underneath the bobbin case and then pulls off from the beak. Except for the thread retaining grooves 27 of the bobbin case, both sides of the bight of needle thread will be carried around the bobbin case without passing underneath the bobbin case and so without engaging the bobbin thread; but the bobbin case being stationary, and the thread retaining grooves 27 being in such position as to engage one side of the loop of needle thread, the bobbin case actually passes completely through the loop of needle thread and then as the needle thread is withdrawn from the loop-taker by the upward motion of the needle, the bobbin thread is looped in the loop of the needle thread.

It will be noted that the loop taker 1 is provided, near the bottom of the thread slot 6, with a pronounced fillet 28, the effect of which is to carry one side of the bight of the loop of needle thread in close to the side of the bobbin case, so causing the needle thread to engage one or another of the thread retaining grooves of that bobbin case.

One advantage of the construction of bobbin case herein described, i. e., the provision of a large number of spring leaves in the side of the bobbin case, is, that in case the

bobbin case becomes worn or the raceway of the loop-taker 1 becomes worn, to such extent that the bobbin case might fly out of the raceway, it is easy by removing the bobbin, 5 and inserting a suitable tapered mandrel in the bobbin case, to spring out the sides of the bobbin case, giving them a permanent set, sufficient to cause them to engage properly in the groove of the loop-taker.

10 What I claim is:

1. The combination with a hook, of a bobbin case adapted to fit within said hook, said bobbin case having side slits forming, in said side, springs, said hook having a rib 15 which said side springs are adapted to engage when the bobbin case is in place within the hook, whereby bobbin case and hook are normally held together.
2. The combination of a hook and bobbin 20 case, the hook adapted to receive the bobbin case within it and having a raceway for such bobbin case and having, beyond said raceway, an inwardly projecting rib, the bobbin case having a projecting flange adapted to 25 work within said raceway and to engage said inwardly projecting rib of the hook, said bobbin case having in its side slits dividing said sides into spring-leaves, whereby the bobbin case is held within the hook by en-

gagement of said spring leaves with the inwardly projecting rib of the hook.

3. A bobbin case comprising a hollow member adapted to receive a bobbin and to fit within a hook, said bobbin case having in its sides, slits dividing such sides into spring 35 leaves, said leaves provided near their end with outwardly extending flanges adapted to engage a portion of a hook into which said bobbin case may fit.

4. The combination with a hook adapted 40 to receive within it a bobbin case, and a bobbin case adapted to fit within said hook, said members, the hook and the bobbin case, provided with spring means for retaining the bobbin case within the hook, said hook 45 provided with an aperture adapted for the insertion of an instrument between the bottom of the bobbin case and the bottom wall of the hook, whereby the bobbin case may be pried out of the hook by an instrument introduced through such aperture.

In testimony whereof I have signed this specification in the presence of two subscribing witnesses.

JAMES LEATHEM.
